UNITED STATES PATENT OFFICE.

SAMUEL TULLY WILLSON, OF DENVER, COLORADO, ASSIGNOR TO THE IMPROVED APPLIANCE COMPANY, OF DENVER, COLORADO.

GAS-BROILER.

No. 799,956.

Specification of Letters Patent

Patented Sept. 19, 1905.

Application filed December 20, 1904. Serial No. 237,722.

To all whom it may concern:

Be it known that I, SAMUEL TULLY WILLSON, a citizen of the United States, residing in the city and county of Denver and State of Colorado, have invented certain new and useful Improvements in Gas-Broilers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in gas-broilers or a device adapted to broil meat by heat produced from the combustion of gas.

Heretofore, so far as I am aware, all of the gas-broilers have been constructed to perform 20 the broiling function only by heat radiation.

In my improvement the broiling function is performed by conduction and convection as well as radiation, since the meat to be broiled lies directly upon the combustion 25 chambers or hoods in which the combustion of the gas takes place. By reason of this construction the meat is marked by the hoods, thus giving it the same appearance as when broiled on an ordinary broiler.

30 Having briefly outlined my improved construction, as well as the function it is intended to perform, I will proceed to describe the same in detail, reference being made to the accompanying drawings, in which is illustrated an 35 embodiment thereof.

In the drawings, Figure 1 is a front elevation of my improved gas-broiler. Fig. 2 is a section taken on the line 2 2, Fig. 1. Fig. 3 is a perspective view of one of the combustion- 40 chambers shown in connection with the gas-conduit and the means for supporting and connecting the hoods. Fig. 4 is a section taken on the line 4 4, Fig. 2. Fig. 5 is a vertical longitudinal section taken through one of the 45 broiling-hoods shown in connection with the gas conduit or supply-pipe, which is partly in section. Fig. 6 is a fragmentary top view of the broiler shown partly in section.

The same reference characters indicate the 50 same parts in all the views.

Let the numeral 5 designate a suitable upright frame, upon the top of which is mounted a series of broiling-hoods 6, which, as shown in the drawings, are wedge-shaped in cross-

section, their smaller extremities being upper- 55 most. These hoods are arranged in suitable proximity and are connected by rivets 7. Through the lower part of each hood passes a gas-conduit 8, perforated, as shown at 9, for the introduction of fuel-gas to the hood. As 60 shown in the drawings, the upper portion of the hood is provided on each side with orifices 10 for the escape of the products of combustion. These orifices are formed by punching out the material of the hood, leaving the lips 12 in- 65 tact at their upper extremities, whereby the products of combustion are first deflected downwardly, thus increasing the heating efficiency of the fuel.

Below the gas-conduits 8 the hoods are perforated, and through these perforations are passed supporting-rods 13, whose extremities engage the top of the frame, and thus support the series of connected hoods in position.

Along the front of the frame is mounted a 75 main gas pipe or conduit 15, from which lead upwardly-projecting nozzles 16, controlled by valves 17. These nozzles project into mixers 18, whose lower extremities are open to allow the air to mingle with the gas in order to furnish the necessary oxygen for purposes of combustion. The upper extremity of each mixer is connected with a T-head 19, from which lead a number of gas-pipes 8 into their respective hoods. As shown in the drawings, 80 each head 19 is connected with four pipes 8, leading to their respective broiling-hoods.

From the foregoing description the use of my improved gas-broiler will be readily understood. The meat to be broiled is laid upon the 90 upper edges of the broiling-hoods and the fuel-gas is turned into the hoods and ignited, whereby the flame from the orifices of the pipes 8 is continually passing upwardly into the hoods, whereby the latter are heated to the necessary 95 extent for broiling purposes, the products of combustion escaping through the orifices 10, as heretofore explained. The grease from the meat is allowed to flow down the sides of the hoods and pass between them into a pan 100 20, mounted on the frame below the hoods. The lips 12 prevent this grease from entering the orifices 10 for the escape of the products of combustion.

My improved construction has a number of 105 advantages over other gas-broilers with which I am familiar, since in the latter the work of broiling is done underneath the fire, whereby

the meat is cooked first on its upper surface, while its under surface remains uncooked, thus allowing the meat-juices to escape. The main or important advantage of broiled meat over that cooked by frying is that the albumin of the meat is coagulated, whereby the pores are stopped, thus preventing the escape of the juices; but where the meat is cooked first on top, as in the ordinary construction of gas-broiler, there is nothing to prevent the escape of the juices at the bottom while the meat is being cooked on its upper surface. In my improved construction the under surface of the meat is cooked first, the same as on a charcoal-broiler, thus effectually preventing the escape of the juices and perfectly performing the broiling function. Again, in the gas-broilers heretofore used the meat has the appearance of being fried rather than broiled, while in my improved broiler the meat is distinctly marked by the tops of the hoods in a manner equal in all respects to the marking resulting from a charcoal-broiler. This streaked appearance of the meat is an important feature.

Having thus described my invention, what I claim is—

1. A gas-broiler comprising a number of combustion-chambers closed at the top where they are narrowest, the said chambers having inclined side walls, gas-pipes located in the respective chambers and open for the escape of gas, the chambers being provided with openings for the escape of products of combustion, the said openings being in their side walls, downwardly-inclined means located above the openings and connected with the chambers to form a shield to prevent the grease from entering the openings.

2. In a gas-broiler, the combination of a number of combustion-chambers suitably connected and supported to form a horizontal broiling-surface, the said chambers being largest at the bottom where they are open and diminishing in size toward the top where they are closed, gas-supply pipes arranged longitudinally in the combustion-chambers, the said chambers being provided with openings for the escape of the products of combustion, and means for shielding the latter against the entrance of the grease from the meat.

3. The combination with a suitable frame, of a series of connected hoods arranged parallel with one another, said hoods being largest at the base and diminishing in size toward the top and provided with openings for the escape of the products of combustion, gas-pipes located in the lower parts of the respective hoods, for supplying the necessary fuel-gas, and supporting-rods passed through the heads below the gas-pipes and having their extremities engaging the frame, substantially as described.

4. The combination with a suitable frame, of a series of hoods suitably supported there-

on, said hoods being largest at the base and diminishing in size toward the top, the tops of the hoods forming the support for the meat to be broiled, gas-conduits located in the lower parts of the hoods for supplying the necessary gas for broiling purposes, heads with each of which a number of the gas-supply pipes are connected, mixers connected with the heads, a main gas-pipe, and valve-controlled nozzles leading from the latter into the mixer, substantially as described.

5. The combination of a series of combustion-hoods largest at the base and tapering upwardly, gas-pipes located in said hoods for supplying the necessary fuel, the heads being connected together in sets, and the bases of each set being suitably separated to allow the grease from the meat above to pass between them, and a drip-pan mounted below the heads for the purpose set forth.

6. A gas-broiler comprising a series of hollow parts separated at the top to form a broiling-surface for the meat, means distinct from the hollow parts and located within the same for supplying the said parts with gas for combustion purposes whereby the broiling-surface may be suitably heated, the said parts being narrowest at the top and sloping downwardly therefrom.

7. A gas-broiler comprising a number of combustion-chambers separated at the top to form a broiling-surface, and pipes distinct from the combustion-chambers and suitably mounted in the said chambers to supply the latter with the necessary gas for combustion purposes.

8. In a gas-broiler, the combination of a series of connected hoods arranged parallel with one another and suitably separated to form a broiling-surface, each hood having a series of openings on its opposite sides formed by punching the metal outwardly, the punched-out metal parts being left intact at the top whereby the openings are shielded from above for the purpose set forth.

9. A gas-broiler comprising a series of hollow parts separated at the top to form a broiling-surface for the meat, means for supplying gas for combustion beneath the said parts whereby the broiling-surface may be suitably heated, the walls of the hollow parts being provided with side openings near the top for the escape of the products of combustion, and means located above the said openings and downwardly inclined to shield the said openings for the purpose set forth.

10. A gas-broiler comprising a number of combustion-chambers, pipes suitably mounted to supply the said chambers from below with the necessary gas for combustion purposes, the tops of the chambers forming a support for the meat to be broiled, the walls of said chambers having openings for the escape of the products of combustion, and means connected with the chambers above the openings

and downwardly inclined whereby the latter are shielded for the purpose set forth.

11. A gas-broiler comprising a number of combustion-chambers open at the bottom 5 while their tops are closed to form the broiling-surface, and means located in the said chambers for supplying the latter with upwardly-directed gas-flame.

12. A gas-broiler comprising a number of 10 combustion-chambers arranged to form a

broiling-surface, said chambers being open at the bottom, and orificed conduits located in the said chambers for supplying the latter with upwardly-directed gas-flame.

In testimony whereof I affix my signature in 15 presence of two witnesses.

SAMUEL TULLY WILLSON.
